CLAIM

The ornamental design for a cartridge magazine cover, substantially as shown and described.

DESCRIPTION

FIG. 1 is a perspective view of a cartridge magazine cover according to the invention.

FIG. 2 is a reversed perspective view of the cartridge magazine cover of FIG. 1.

FIG. 3 is an inverted perspective view of the cartridge magazine cover of FIG. 1, showing the reverse face design.

FIG. 4 is a one end elevational view.

FIG. 5 is a plan view showing the reverse face design of the cartridge magazine of FIG. 1.

FIG. 6 is an opposite end elevation as viewed at the left end of the cover as shown in FIG. 5.

FIG. 1
